UNITED STATES PATENT OFFICE.

JOSIAH DAWSON, OF PHILADELPHIA, PENNSYLVANIA.

FUSIBLE LINK.

Application filed March 5, 1921. Serial No. 449,755.

To all whom it may concern:

Be it known that I, JOSIAH DAWSON, a citizen of the United States, and a resident of the city of Philadelphia, county of 5 Philadelphia, and State of Pennsylvania, have invented certain new and useful Improvements in Fusible Links, of which the following is a specification, reference being had to the accompanying drawing.

10 My invention relates to fusible links for automatic sprinkler heads, fire doors and other apparatus designed to function upon the heat actuated release of a link or other device normally under tension, among its principal objects being to provide a link of extremely 15 simple construction which may be manufactured at a low cost and embodying means other than the fusible metal or solder by which the members of the link are normally held in assembled relation for resisting the longitudinal strain or tension to which the link is normally subjected when in use. Further objects of the invention are to provide a link embodying a key or strain 20 resisting member of the character aforesaid in which the member is so arranged that when the link is assembled and soldered together a portion of the member is readily visible so that it may be readily observed 25 whether or not the member has been properly assembled in the link and is, in fact, in position therein.

Still further objects of my invention are to provide a link for the purposes aforesaid comprising members adapted to be united by fusible metal and embodying means effective to bring about the rapid and positive separation of the members upon the fusing of the metal.

40 My invention further includes all of the other objects and novel features of construction and arrangement hereinafter more definitely specified and described.

In the accompanying drawings I have 45 illustrated certain forms of the invention, Fig. 1 being a front elevation of a preferred form thereof with the parts in assembled position and united by solder or other suitable fusible material; Fig. 2 is a side elevation of the assembled link shown in Fig. 1 in operative position on the arms of a sprinkler head; Fig. 3 is a side elevation of the link and sprinkler head arms showing the action of the parts of the former after 50 the fusing of the solder; Fig. 4 is a view similar to Fig. 3 but in central vertical sec-

tion; Fig. 5 is a composite view showing in full lines and in elevation the several parts of this form of the link prior to assembly, and Fig. 6 is a perspective view of 60 one of the parts thereof. Fig. 7 is a composite view similar to Fig. 5 showing a slightly modified form of the invention; Figs. 8 and 9 are views thereof respectively 65 similar to Figs. 2 and 4, and Fig. 10 is a composite view similar to Figs. 5 and 7 but showing a still further slightly modified form of the invention. Like numerals are 70 used to designate corresponding parts in the several figures.

The form of the invention shown in Figs. 1 to 6 inclusive comprises a pair of plates 1 and 2 which are preferably blanked out from sheet bronze or other suitable material in any convenient manner, and while these 75 plates may be of any suitable contour I prefer to make them of substantially the shape shown. Conveniently this may be accomplished by initially giving the plates a similar outline as indicated by the dotted lines 80 ing Fig. 5, the point of greatest width of each plate being located nearer one end thereof than the other, and preferably so that the distance from such point to one end of the plate is substantially twice that to 85 the other end. From this point of greatest width the adjacent lateral edges of the plate respectively converge in opposite directions toward the ends, so that the plate presents a generally kite-shaped appearance, the angle between the converging edges adjacent one end being considerably greater than at the other. Either simultaneously with the blanking operation just described or in a 90 separate operation, one of the plates as, for 95 example, plate 1, is provided with an aperture 3 adjacent its obtuse end and the other plate with a preferably similar aperture 4 adjacent its narrow end, and the end of each plate opposite to that adjacent the aperture is respectively cut off in a more or less generally transverse direction, as at 5 and 6, so that when the plates are turned end for 100 end and disposed one upon the other with their respective faces X and Y adjacent as 105 in Fig. 1, the edge 5 will lie adjacent the aperture 4 and the edge 6 adjacent the aperture 3 leaving both apertures free for the passage of the sprinkler head arms.

Each plate in this form of the invention 110 may be provided with a pair of preferably parallel laterally spaced slots positioned sub-

stantially equidistant from the ends of the plate, the slots in plate 1 being designated as 10 and those in plate 2 as 12. The slots in each plate are located on opposite sides 5 of its center line and the metal lying between the slots is struck outwardly to provide a curved portion 14 extending beyond the outer surface of the plate and forming a substantially semi-cylindrical depression 10 or cavity 15 lying between the slots adjacent the inner surface of the plate, these depressions and the adjacent slots being so disposed in the respective plates that when the latter are assembled, the slots in each 15 plate will align with those in the other, the two semi-cylindrical depressions thus forming a substantially cylindrical opening extending transversely of the plates and bounded by the struck-out portions 14.

20 Within this opening is positioned what for convenience may be termed the key member which is best shown in Fig. 6 and comprises a spool having a cylindrical body 20 and outwardly directed preferably integral flanges 21 of similar diameter positioned at the ends thereof. The diameter of the body 20 is preferably substantially that of the cylindrical opening formed between the struck-out portions of the respective plates, while the diameter of the flanges 25 21 is preferably very slightly less than the length of the slots 10 and 12. Moreover the total over-all length of the key member is preferably very slightly less than the distance between the outer edges of each pair 30 of slots and the length of the body portion 20 slightly greater than the width of the struck-out portion 14 so that when the key member is positioned between the plates 35 and centrally disposed with respect thereto, there preferably is a very slight clearance 22 between the outer faces of the flanges 21 and the outer sides of the slots and a similar clearance 23 between the inner 40 sides of the slots and the inner faces of the flanges.

45 When assembled, the several elements composing the link are united in the ordinary manner by solder or other fusible metal 50 25 which is distributed between the adjacent faces of the plates and also ordinarily flows out through the clearances 22 and 23 and collects on the surface of the plates adjacent the ends of the key member as indicated at 55 27, 28. It will be evident that with the parts assembled in the manner described, portions of the flanges of the key member will at all times be visible above the small amount of fusible metal 27, 28 which ordinarily 60 collects on the outside of the plates during the soldering operation, so that it may be readily ascertained by inspection at any time whether or not the key member has been properly positioned between the plates in the assembling process. Hence

the danger of assembling on a sprinkler head for operative use a link from which the key member has been omitted through carelessness or oversight during assembly is avoided, as a very cursory inspection will readily 70 reveal the presence or absence of the key member.

The link is now in condition to be placed in operative position, for example upon the arms A, B of a sprinkler head with the 75 ends of the arms projecting through the apertures 3 and 4, in which position the normal tendency of the arms to move outwardly in opposite directions, due to the construction of the head as will be readily 80 understood by those familiar with the art, subjects the link to longitudinal tension or strain which, in the absence of the key member, might cause the solder to give way and permit either total separation of the 85 plates or else a slight relative longitudinal creeping resulting in leakage of the sprinkler head. The interposition of the key member, however, is effective to relieve the strain on the solder thus assuring the 90 relative immobility of the several parts of the link so long as the temperature in the vicinity thereof remains below the fusing point of the solder.

Upon an increase of the temperature in 95 the vicinity of the link sufficient to cause the fusing of the fusible metal which unites the plates, the strain exerted on them by the sprinkler head arms immediately causes a relative longitudinal movement of the 100 plates in opposite directions which is effective to cause the inner edges of the lower ends of the slots 10 to ride up on the peripheries of the flanges 21 of the key member and the inner edges of the upper ends 105 of the slots 12 to similarly ride up at a substantially diametrically opposite point on the flanges as shown in Figs. 3 and 4, and as the relative longitudinal displacement of the plates progresses, the said edges of 110 the respective slots continue to ride up upon the edges of the flanges whereby the plates are rapidly and positively forced apart in a direction substantially at right angles to their plane of relative longitudinal movement, the flanges, in effect, forming cams 115 operative to force the plates apart. By reason of the relatively large diameter of the flanges the plates are thus positively moved apart for a distance sufficiently great 120 to prevent the fused solder, which is immediately chilled by the rush of water from the head which follows the initial movement of the arms, from reuniting the plates and thereby preventing the proper functioning of the head by checking the flow therefrom before it reaches its maximum intensity, and as the ends of the slots when 125 the link is assembled lie either in contact with the flanges or very slightly spaced 130

therefrom, the outward movement of the plates commences substantially simultaneously with their longitudinal movement thus insuring their positive and complete separation substantially simultaneously with the fusing of the fusible metal.

In Figs. 7 to 9 inclusive is shown a slightly modified form of the invention which is substantially similar in all respects to the form of the invention hitherto described save that the metal in one of the plates, for example plate 1, is struck outwardly adjacent the outer edges of the slots 10 thus providing a curved, preferably substantially semi-cylindrical portion 30 adjacent the outer edge of each slot which bounds a corresponding depression or cavity 31 in the inner face of the plate. In order that, when the plates are assembled on each other, their adjacent surfaces may be brought together, the other plate adjacent the outer edge of each of the slots 12 is cut out as at 32 to provide apertures through which the struck-out portions 30 may extend, as best shown in Fig. 8. When the link is assembled and the several parts united by the fusible material, a quantity of the latter may be deposited in each of the depressions 31 adjacent the ends of the flanges 21 of the key member, thus forming a relatively considerable mass of fusible material adjacent the ends thereof which tends to very firmly retain the key member in position. The operation of this form of the invention is substantially similar in all respects to that of the form previously described, and will be readily comprehended by reference to Figs. 8 and 9.

In Fig. 10 I have shown a still further slightly modified form in which but a single slot 35 is provided in each plate, the metal adjacent either side of the slot being struck outwardly as at 36 to provide substantially semicylindrical cavities or depressions in the faces X and Y of the plates, so that when the latter are brought together a substantially cylindrical cavity will be formed adjacent each side of the slot adapted to receive the cylindrical portions 39 of the key member. The latter is provided between the portions 39 with an outwardly directed flange 40 which enters the slots 35 in a manner similar to that in which the flanges 21 enter the slots 10 and 12, and is similarly effective to force the plates apart by a sort of camming action upon the fusing of the fusible metal which normally unites the various elements in assembled position.

While I have herein described and illustrated in the accompanying drawing certain embodiments of my invention with considerable particularity and have shown the same in connection with the arms of a sprinkler head, I do not thereby desire or intend to limit myself to any precise details

of construction and arrangement of the several parts nor to the use of plates of any particular contour, as the former may be varied in minor particulars as desired, plates of other contours than those illustrated may be employed and the link used in connection with fire doors and other devices without departing from the spirit and scope of the invention as defined in the appended claims.

Having thus described my invention I claim and desire to protect by Letters Patent of the United States:

1. A fusible link comprising a pair of plates united by fusible material, each plate having a slot and a cylindrical key member having an outwardly directed peripheral flange disposed between the plates with said flange projecting into said slots.

2. A fusible link comprising a pair of plates united by fusible material, each plate having a pair of slots, and a cylindrical key member disposed between the plates and having peripheral flanges projecting into said slots.

3. A fusible link comprising a pair of oppositely disposed plates united by fusible material, each plate having a slot and an outwardly struck portion adjacent thereto, said portion bounding a depression formed in the inner face of the plate, and a cylindrical key member having peripheral flanges and positioned between the plates partially in said slots and partially in said depressions.

4. A fusible link comprising a pair of oppositely disposed plates united by fusible material, each plate having a slot and a depression adjacent thereto in its inner face, and a cylindrical key member having portions of different diameters positioned between the plates partially within the slots and partially within the depressions.

5. A fusible link comprising a pair of plates united by fusible material, each plate having a slot on each side of its median line and a key member positioned between the plates and having outwardly directed flanges entering said slots when said plates are assembled and adapted under operative conditions by engagement with the ends of said slots to cam said plates apart when said fusible material is fused.

6. A fusible link comprising a pair of plates adapted to be united by fusible material, each plate having a pair of slots disposed on opposite sides of its median line, the material of which each plate is formed being struck outwardly between the slots so as to provide a depression in the inner face of the plate extending transversely between the slots, and a key member comprising a body portion and outwardly directed cylindrical flanges, said body portion being adapted to rest in the aperture formed between the outwardly struck portions of the

plate and the flanges to enter said slots when the link is assembled.

7. A fusible link comprising a pair of plates each having a pair of parallel slots disposed on opposite sides of its median line, a depression formed in each plate between the slots therein and a key member having a portion adapted to enter said depression and other portions adapted to enter said slots when the plates are assembled to form the link.

8. A fusible link comprising a pair of plates each having a pair of parallel slots disposed on the opposite sides of its median line, and a key member having a body portion adapted to extend transversely between the slots and outwardly directed cylindrical flanges adapted to enter the slots when the plates are assembled to form the link.

20. 9. A sprinkler head link comprising a pair of plates adapted to be united by fusible material, each plate having a pair of parallel slots disposed on the opposite sides of its median line, the material from which 25 the plate is formed being struck outwardly between the slots to form a semi-cylindrical depression in the inner face of the plate, and a key member comprising a cylindrical body portion and an outwardly directed 30 flange adjacent each end thereof, said body portion being adapted to rest in said semi-cylindrical depression and said flanges to enter said slots and extend beyond the outer faces of the plates when the plates are assembled to form the link.

35. 10. A sprinkler head link comprising a pair of plates adapted to be united by fusible material, each plate having a pair of

slots disposed on opposite sides of its median line, the material from which the plate is 40 formed being struck outwardly between the slots to provide a substantially semi-cylindrical depression in the inner face of the plate extending transversely of the slots, and a key member having a cylindrical body 45 portion adapted to rest in the cylindrical aperture formed between the plates when the latter are assembled to form the link and a pair of outwardly directed flanges of 50 greater diameter than said body portion adapted to enter said slots and to extend beyond the outer faces of the plates whereby said flanges are visible above the outer surfaces of the plates when the link is assembled, the inner edges of the ends of the 55 slots being operative to ride on said flanges when the plates of the link are moved longitudinally in opposite directions.

11. A fusible link comprising a pair of complementary plates adapted to be united by fusible material, each plate having a pair of parallel slots disposed on opposite sides of its median line and a depression formed 60 between the slots, and a key member adapted to rest in said depression and having outwardly directed flanges adapted to enter said slots when the link is assembled, the inner edges of the ends of the slots being 65 operative to ride on the edges of the flanges to force said plates apart simultaneously 70 with a relative longitudinal movement of the plates.

In witness whereof, I have hereunto set my hand this third day of March, A. D. 1921.

JOSIAH DAWSON.
